ISAAC M. ROD, OF DUBLIN, PENNSYLVANIA

ART OF MAKING GARMENTS

Application filed January 5, 1927. Serial No. 159,048.

My invention is designed to provide an improved garment edging by a new and useful method, and it comprises a novel method of affixing a lining and a stiffening fabric to the free edges of garments by machine stitching, and more particularly for affixing a lining and a stiffener to the upper free edge of the waistband of trousers by but a single row of machine made stitches, whereby the finished 10 edge seam will not only closely simulate a hand stitched seam, but will also possess the characteristic advantages of hand stitched or "hand finished" seams.

My invention further relates to novel apparatus for carrying out my method; said apparatus being adapted to be attached to, and to coact with, standard or conventional sewing machines; and comprising a novel combination of lining, folding and guiding means, 15 and means coordinated with each other for guiding the cloth of the garment, a band of stiffening material and a band of lining material, in predetermined and fixed relation to each other, to the sewing point of the sewing 20 machine.

In forming seams along the upper edges of the waistband of trousers, whereby the waistband lining material as well as the intermediate stiffening fabric were affixed to 25 the edge of the cloth or fabric of the waistband portion of the trousers, two methods have been commonly applied heretofore. One method was known as a "machine finished" method, which was relatively inexpensive, and whereby the lining band and a stiffening band were separately superimposed upon the outer surface of the fabric of the trousers, with the edges of the three plies aligned with 30 each other and extending in the same direction. By this machine method, a row of machine stitches were applied to the three superimposed layers along and adjacent to the edges thereof. Lastly the three layers were 35 reversed so as to position the stiffening fabric intermediate of the lining and the cloth of the trousers, thereby positioning the free edges of the cloth, stiffening and the lining intermediate of the stiffener and the cloth, and concealed from view. While this method 40 was a relatively inexpensive one, the edge 45

seam produced thereby was relatively thick and bulky and did not possess a well defined and uniformly straight edge. Moreover, by this method the intermediate stiffening fabric was folded or doubled within the seam. 55

In order to overcome the disadvantages of the machine made seam as described above, hand finishing has been resorted to for producing the better class of work. By this second method known as hand finishing, lining 60 was superimposed upon the cloth, with the edges substantially aligned and extending in the same direction, and the edges of the cloth and lining were then superimposed upon the edge of the stiffening fabric, overlapping the 65 same a suitable extent, and the three layers were then basted together by hand for temporarily securing the same. Thereafter the cloth of the garment or trousers was bent or folded along the free edge of the stiffening 70 fabric, while the lining was folded back upon itself and in the same direction, and the folded edge of the lining was then affixed to the folded edge of the cloth by a series of hand stitches. The basting thread was then 75 removed from the seam. While the resulting seam was relatively thin, and otherwise also more desirable than the machine made 80 seams employed heretofore, since the stiffening fabric was not folded back upon itself, 85 it was considerably more expensive to produce. 90

The object of my invention is to provide a garment edging, and a method and means of affixing the lining and stiffening fabric 95 to the edges of cloth, to produce said garment edging, which will possess the structural advantages and the desirable characteristics of the hand finished seamed edgings used heretofore, and which at the same time will possess the economical advantages of the machine made seamed edgings produced heretofore. 100

A further object of my invention is to produce a machine stitched lining in the 105 waistband portions of trousers, and more particularly to so affix the upper edge of said lining as well as of an intermediate stiffener to the fabric of the trousers or other garments, entirely by machine stitching, as to 110

produce a seam along the free edge of the waistband, which will be uniformly straight, in which the fabric of the trousers will be bent around, and supported by, a single thickness of the inner or intermediate stiffening fabric, and whereby the said seam will not only closely simulate the hand felled seams but will also possess all the advantages thereof.

Thus by my present invention, I am enabled to line the waistband of trousers, by a single machine operation, and thereby produce a seamed edge having all the desirable characteristics and appearance of "hand finished" trousers, and to produce the same at a small fraction of the cost of the hand finished seams.

The characteristic features and advantages of my improvements will more fully appear from the following description and the accompanying drawings illustrating a preferred embodiment of my invention, and in which Fig. 1 represents a top plan view of the novel apparatus embodying my invention, showing the manner in which cloth of the garment and the lining band, as well as the stiffening band, are affixed; Fig. 2 represents a vertical section on line 2--2 of Fig. 1; Fig. 3 represents a section on line 3--3 of Fig. 1; Fig. 4 represents a front elevation of the folding device of my novel apparatus; Fig. 5 represents a diagrammatic cross-section of the fabric of the trousers as well as of the lining band and stiffening band, after the latter two have been affixed to the edge of the cloth, by the novel apparatus and method of my invention; Fig. 6 represents a diagrammatic cross section similar to that shown in Fig. 5 with the cloth of the trousers folded around the stiffening fabric, showing the relation of the three plies of fabric in the finished condition; Fig. 7 is a side elevation of the novel apparatus of my invention on a reduced scale, and illustrating the manner in which the rolls of lining band and stiffening band are supported and fed to the folding device comprised in my novel apparatus, and the general manner in which said two bands are guided to the common sewing point of the sewing machine where the edges thereof are affixed to the edge of the cloth of the garment, in a predetermined and affixed relation to each other; Fig. 8 represents a top plan view of a presser-foot forming part of my invention, illustrating the manner in which the folded edge of the lining is guided beneath the presser-foot, through a guide or gage slot in said presser-foot.

In carrying out my invention, I provide a novel folding and guiding attachment, adapted to be secured to the metallic table 1 of a standard or conventional sewing machine, said folder comprising a base plate 2, adapted to be fastened or clamped onto the table 35 of the sewing machine, by suitable screws

passing through apertures 3 therein, and threaded into the table 1 of the sewing machine.

The base plate 2 comprises a relatively thick and parallel walled portion 4 and a relatively thin parallel walled and raised portion 5, having the lower surface thereof offset and raised from the lower surface of the portion 4. Thus, when the base plate 2 is clamped to the flat upper surface of the table 1 of the sewing machine, the portion 5 of said base plate will be raised and spaced from the surface of the table 1 of the sewing machine, and will extend substantially parallel thereto.

An adjustable gage plate 6 is provided, of a thickness substantially equal to the offset of the portion 5 of the base plate 2, and is secured beneath the free end 7 of the base plate 2 in an adjustable manner, by means of a screw 8 passing through a suitable elongated aperture in said free end 7 of the base plate 2, and threaded into said gage plate 6. Gage plate 6, thus secured to the free outer end of the base plate 2, forms a parallel channel 16, beneath the raised portion 5 of the base plate 2, between the shoulder 8, and the edge 9 of said gage plate.

A parallel band of stiffening material, to be described more in detail hereinafter, is passed beneath the base plate 2, in the channel thus formed, and said stiffening band is thereby guided in proper spaced relation to the lining fabric band as well as to the cloth of the garment.

The gage plate 6 is provided with the turned up rear end flange 10 which bears against the rear edge 11 of the base plate 2, thereby to align the gage plate 6 with respect to said base plate. A second aligning flange 12 is also provided at the other end of the gage plate 6, formed by turning upwardly a projecting portion of the inner longitudinal edge of said gage plate 6, and said flange 12 in turn bears against the front edge 13 of said base plate.

In order to aid in aligning the folding device of my novel construction, with respect to the edge of the table 1 of the sewing machine, a downwardly depending aligning lug or gage projection 14 may also be formed on the gage plate 6, by turning downwardly a projecting terminal portion thereof. The gage projection 14 bears against the edge 15.

The folding device or apparatus of my invention further comprises an inclined aligning folder 17, disposed above and in operative alignment with the guiding channel 16. The lining folder 17 is carried by a V shaped bracket 18, the horizontal portion 20 of which is adjustably secured to the raised portion 5 of the base plate 2, by means of a pair of screws 21 extending through corresponding elongated apertures in the horizontal portion 130

20 of the bracket and threaded into the raised portion 5 of the base plate 2.

The inclined lining folder 17 comprises two parallel and spaced walls 22 and 23 respectively, substantially coextensive with each other. The lower wall 23 is provided with a slightly inclined and folded edge 24, as shown particularly in Figs. 1 and 3, while the upper wall 22 is provided with a corresponding rolled and inclined edge 25, which extends around, and is spaced from, the edge 24 of the lower wall 23, and is rigidly secured thereto on the lower surface thereof, at a slight distance from the free edge 24 of said lower wall 23. The guiding slot 26 formed between the spaced walls 22 and 23, is thus terminated at one end in an inclined folding slot 27, having a generally curved contour and extending parallel to the slot 26 a slight distance.

20 A spacing plate 28 is disposed between the free and unattached ends of the walls 22 and 23, having an aligning flange 29 extending at a right angle thereto and adapted to bear against the upper edge 30 of the lower wall 23 thereby to maintain the longitudinal edge 31 of the spacing plate 28, at a right angle to the horizontal edge 30 of the wall 23. The walls 22 and 23 are provided with slightly elongated and aligned apertures for receiving a screw 32, which extends through a washer 33, walls 22 and 23, and the intermediate separating or spacing plate 28, and is threaded into an anchor plate 34. After properly adjusting the spacing plate 28, to the particular width of the lining fabric band, the screw 32 is tightened, thereby locking the spacing plate 28 in position and thereby also firmly securing the free, unattached ends of the walls 22 and 23.

45 The lower and upper horizontal edges 35 and 36 respectively of the upper wall 22 may be flared upwardly to a slight extent, thereby facilitating the passage of the lining band or fabric, through the lining guide slot 26.

The combined lining folder and stiffener band guide described above, and designated generally by the numeral 37, is secured to the table 1 of the sewing machine, by means 50 of a pair of screws 38, so that the lower terminal 39 of the inclined edge 24 of the wall 23, that is the edge delivery point of the slot 26, will be in substantial alignment with the sewing point or needle 40 of the sewing machine, and spaced slightly in advance of the presser-foot 41. The lining folder 17 is also adjusted upon the base plate 2, by means of the screws 21, so that the delivery point 39 of the slot 26 of said folder 17, will be spaced 55 inwardly a slight distance from the guiding shoulder 8, of the guiding channel 16; that is, so that the guiding channel 16 will project a slight distance beyond the point 39.

60 The lining band 42, is delivered from an upper supply roll 43, carried above the sew-

ing machine by any suitable means, and is extended through the slot 26 of the folder 17, in the manner shown particularly in Fig. 7, with one edge thereof extending into the folding slot 27, and thereby folded over upon itself. The stiffening band 44 of any suitable sized-fabric or the like, is similarly supplied from a lower roll 45, carried by any suitable means beneath the sewing machine and is passed through the guiding channel 16 of the base plate 2.

70 The presser-foot 41, carried by the presser rod of the sewing machine in the usual manner, is provided with the elongated aperture 46, through which the needle 40 of the sewing machine may project, and is also provided with a slot 47 slightly in advance of the sewing needle 40 and aperture 46, through which the folded edge 48 of the lining band 42 extends. Thus, as the lining tape 42 is delivered from the lower end of the slot 26 in the folder 17, the folded edge 48 thereof, passes into the slot 47 in the pressure-foot 41, and thence passes beneath the presser-foot. The inner edge 49 of said slot 47, acts as a guide or gage for the edge 48 of the lining band 42, thereby accurately aligning said edge 48 with the needle or sewing point 40 of the sewing machine.

75 While my improved apparatus, as well as the novel method carried out thereby, are applicable to any standard or conventional sewing machine, in the preferred embodiment of my invention a sewing machine known as the "zig-zag" sewing machine is employed. The 80 needle of this type of sewing machine, as is well known in the art, is moved back and forth between two laterally spaced sewing positions thereof, between successive downward strokes of the needle. This lateral displacement of the needle between successive downward strokes thereof, combined with the longitudinal movement of the cloth, produces a series of stitches disposed at angles to each other, or what are known as "zig-zag" stitches. 85 The cloth is thus pierced successively in two different and slightly spaced longitudinal lines, the threads of the stitches extending from one line to the other at uniform angles.

90 In order to simulate what is known as "hand finishing" in the application of the lining band 42 to the waistband portion of the trousers, the delivery point 39 of the folder 17, is so adjusted with respect to the needle 40 that the said needle 40 will pierce the lining 95 100 105 110 115 120 125 130 42 only in one of the two rows of the stitches, while the other row of stitches produced by said needle will be disposed beyond the edge of the lining. By this means the overcast band stitch is closely simulated.

The waistband portion 50 of the cloth is then placed over the thick portion 4 of the base plate 2, and is passed beneath the presser-foot 41. The free edge 51 of the cloth 50 is held against a fixed gage or stop 52, car-

ried by the base plate 2 in predetermined and fixed relation to the delivery point 39 of the folder 17, so that the folded edge 48 of the lining 42 will overlap and be superimposed upon the free edge 51 of the cloth 50. The fixed gage 52, and the delivery point 39 of the folder 17, as well as the guiding edge 8 of the guide channel 16, are so adjusted relatively to each other, that the edge 53 of the stiffening fabric or band 44, projects beyond the folded edge 48 of the lining band 42 to a suitable extent, and also projects beneath and in lapping relation to the free edge 51 of the cloth 50, as illustrated more particularly in Figs. 1 and 5.

By this novel colocation of the edges 48, 51 and 53 with respect to each other and with respect to the needle or sewing point 40 of the sewing machine, a row of zig-zag stitches is produced, extending through the folded edge 48 of the lining as well as through the stiffening fabric 44 along the points 54, and extending through the free edge 51 of the cloth 50, and the stiffening fabric 44, along the alternate points 55 thereof. After leaving the needle 40, or the sewing point of the machine, the lining 42 and the stiffening band 40 are in the condition shown diagrammatically in Fig. 5.

After the entire waistband of the trouser is thus provided with a lining band 42 and a stiffener band 44, the fabric or cloth 50 of the trousers is folded around the free edge 53 of the stiffener fabric band 44, and is disposed adjacent to the opposed surface of the stiffener fabric, thereby positioning said stiffening fabric 44 intermediate of the lining band 42 and the cloth 50, in a manner shown diagrammatically in Fig. 6. By thus folding over the cloth 50, a well defined and uniform finished edge 56 is produced along the upper edge of the waistband of the trousers, said edge being supported by the free edge 53 of the stiffening band 44 within, or intermediate of, the cloth 50 and the lining 42, with avoidance of the bulkiness incident to the finishes heretofore commonly used.

Moreover, by this novel method of affixing the lining band as well as the stiffening band to the waistband of the trousers, the stitches 57 are not visible from without, while from within a row of zig-zag stitches appear closely simulating hand felling. Furthermore by this novel construction, the stiffening band 44 is disposed between the cloth 50 of the waistband of the trousers and the lining 42, in but a single layer and is unfolded at its edges. Due to the absence of any folded edges of the stiffener band 44, a much thinner and neater finished edge 56 is produced along the free edge of the waistband of trousers.

It will be seen from the foregoing therefore that by my novel method of affixing the lining band as well as the stiffener band to the

free upper edge of the waistband of trousers, or to the free edges of the cloth of garments in general, a seam is produced between lining and the cloth, as well as between the stiffening layer, which in addition to possessing the structural advantages and the desirable appearance and neatness of a hand stitched seam, can be produced at a small fraction of the cost and in a small fraction of the time required for hand felled seams.

By cutting the lining fabric 42 on the bias, so that the wales or ribs of the fabric will give a twilled effect and extend substantially parallel with one of the sets of alternate stitches of the zig-zag type, the "hand finished" or overcast stitch effect is further accentuated, due to the partial concealment or embedding of one of the sets of zig-zag stitches, between the ribs of the lining fabric.

Having described my invention, I claim:

1. A garment edging comprising a plurality of plies of fabric having inturned edges, a ply of stiffening fabric housed between said plies first named and under one of said inturned edges, and a single row of machine stitching securing said plies together and visible from one side of the edging and invisible from the other stitches aforesaid alternately engaging one of said inturned edges to said stiffening fabric and both of said inturned edges to said stiffening fabric.

2. A garment edging comprising a plurality of plies of fabric having inturned juxtaposed edges, a ply of stiffening fabric housed between said plies first named and under one of said inturned edges, said plies being connected at their upper edges only by a row of zig-zag stitches connecting said plies together; one of said first named plies of fabric having spaced ribs extending substantially parallel with one set of the zig-zag stitches.

3. A garment edging comprising a plurality of plies forming an outer fabric and a lining having inturned juxtaposed edges, a ply of stiffening fabric housed between said plies first named and extending under one of said inturned edges, and a row of zig-zag stitches connecting the inturned edge housing said stiffening fabric member with said stiffening member and the inturned edge of the lining ply, said row of zig-zag stitches being visible from the lining side of said edging and invisible from the outer fabric side thereof, and stitches aforesaid alternately engaging one of said inturned edges to said stiffening fabric and both of said inturned edges to said stiffening fabric.

4. A garment edging comprising a body fabric ply and a lining fabric ply having inturned juxtaposed edges, the edge of said body ply extending slightly beyond the edge of said lining ply, a ply of stiffening fabric between said body and lining plies, and ex-

tending under and supporting the inturned edge of said body ply, and a row of zig-zag stitches connecting the inturned portion of the edge of said body ply with said stiffening ply and the inturned edge of said lining ply, said row of zig-zag stitches being visible from the lining side of edging and invisible from the outside thereof and stitches aforesaid alternately engaging one of said inturned edges to said stiffening fabric and both of said inturned edges to said stiffening fabric.

5. The method of affixing the lining to garments, which consists in overlapping the free edge of the garment fabric upon an edge of a stiffening fabric a suitable limited extent, folding under the edge of a lining fabric, superimposing said lining upon said stiffener, with the folded under edge there-
 10 of disposed in overlapping relation to said free edge of the garment fabric, to a lesser extent however than the stiffener fabric, and with said folded under edge of the lining immediately adjacent to the garment fabric,
 15 applying a row of machine stitches through the folded edge of said lining, said garment fabric and said stiffener and lastly positioning said three fabrics in laminated relation to each other with the stiffener disposed in-
 20 30 intermediate of said other two fabric plies.

6. The method of affixing the lining to garments, which consists in overlapping the free edge of the garment fabric upon an edge of a stiffening fabric a suitable limited extent, folding under the edge of a lining fabric, superimposing said lining upon said stiffener, with the folded under edge thereof disposed in overlapping relation to said free edge of the garment fabric, to a lesser extent
 35 however than the stiffener fabric, and with said folded under edge of the lining immediately adjacent to the garment fabric, applying a row of zig-zag stitches through the folded edge of said lining, said garment fabric and said stiffener and lastly positioning said three fabrics in laminated relation to each other with the stiffener disposed in-
 40 45 intermediate of said other two fabric plies.

7. A garment edging comprising a plurality of plies of fabric having inturned juxtaposed edges, a ply of stiffening fabric housed between said plies first named, and a row of stitches connecting said plies together, some of the stitches aforesaid engaging both of said inturned edges to said stiffening fabric; and other of the stitches aforesaid engaging but one of said inturned edges to said stiffening fabric.

8. The method of forming a garment edging which comprises lapping a plurality of fabrics and a stiffener, alternately stitching through both said fabrics and said stiffener, and then through but one of said fabrics and said stiffener, and folding one of said fabrics relatively to said stiffener.

9. The method of forming a garment edging which comprises lapping a lining and a stiffener on opposite surfaces of fabric adjacent to the edge thereof, said lining lapsing said fabric less than said stiffener, ⁷⁰ stitching said lining, fabric and stiffener together, and folding said fabric on said stiffener.

In testimony whereof I have hereunto set my name this 16th day of December 1926. ⁷⁵
